CLAIM

We claim the ornamental design for a track for traction of a vehicle, as shown and described.

DESCRIPTION

FIG. 1 is a front perspective view of a track for traction of a vehicle in accordance with a first embodiment of the design;

FIG. 2 is a rear perspective view of the track of FIG. 1;

FIG. 3 is a top view of the track of FIG. 1;

FIG. 4 is a bottom view of the track of FIG. 1;

FIG. 5 is a right side elevation view of the track of FIG. 1;

FIG. 6 is a left side elevation view of the track of FIG. 1;

FIG. 7 is a front perspective view of a track for traction of a vehicle in accordance with a second embodiment of the design;

FIG. 8 is a rear perspective view of the track of FIG. 7;

FIG. 9 is a top view of the track of FIG. 7;

FIG. 10 is a bottom view of the track of FIG. 7;

FIG. 11 is a right side elevation view of the track of FIG. 7; and,

FIG. 12 is a left side elevation view of the track of FIG. 7. The broken lines depict environment subject matter only and do not form part of the claimed design.
